ILLUMINATING AIMING ATTACHMENT FOR FIREARMS

Carl Benton Osborn, Tampa, Fla.

Application May 4, 1936, Serial No. 77,871

7 Claims. (Cl. 240—6.41)

The invention forming the subject matter of this application is in the nature of an attachment for firearms in general, and more particularly relates to illuminating aiming attachments designed 5 to be applied to small arms to facilitate their being aimed at a target at night-time or when lighting conditions are below normal.

The main object of the invention is to make available for the aiming of firearms the varying intensities of light and shade found in the pattern of light thrown by the common types of flashlights that have facilities for focusing the light beam issuing therefrom; by causing the aim of the firearm to be directed upon a distinctive 15 spot of light or shade of relatively small area that in the focusing of such flashlights is made to appear within the larger area illuminated by the light beam. The distinctive spot mentioned may result from adjusting the light beam slightly out 20 of focus producing a dark or shade spot; it may be the result of drawing the light beam down to a small or fine focus, producing a contrastingly vivid and relatively small spot of light in the approximate center of the general illumination, or it may be a contrasting and easily distinguishable spot of either light or shade caused by unequal refraction of the glass through which the light beam leaves the flashlight, or it may be the 25 result of other causes.

To the end above set forth, an attachment is provided which can be applied to a small arm of the pistol, automatic pistol, or revolver type and to such arms as rifles, shotguns or arms of any type adapted for use with an illuminating, aiming 30 device without necessitating any change in construction of the arm, such attachment also embodying means for supporting a flash-light of common construction and provided with means of focusing the beam of light emanating from 35 such flashlight, and without any change in the construction of such flashlight, in such position that such flashlight may be adjusted in various 40 directions to enable a distinctive spot in its light pattern to be made to coincide with the aim of the firearm which is held rigidly in said attachment by means provided.

With the flashlight so adjusted that the said distinctive spot coincides with the aim of the 45 firearm in the plane of the object to be fired at, it is obvious that merely holding the spot upon the 50 said object simultaneously directs the aim of the firearm upon that object, so that the firearm is thus aimed quickly and accurately without reference to the sights usually provided as a part of 55 or as parts of the firearm for directing the aim thereof, and the object to be fired upon may be struck simply by holding the spot upon said object and discharging the firearm.

Another object of the invention is to provide, 60 in an attachment of the character referred to, a

means adjacent to the trigger mechanism of the firearm whereby the user can operate the flash-light independently of or simultaneously with the operation of the trigger of the firearm.

Other objects of the invention will become apparent as the detailed description thereof proceeds.

In the drawing:

Figure 1 is a side elevation of a firearm of the revolver type having the attachment which forms 10 the present invention applied thereto;

Figure 2 is a sectional side elevation similar to Figure 1, but with the adjustable connecting part shown in vertical section;

Figure 3 is a bottom plan view of the attachment 15 shown in Figures 1 and 2, but with the flashlight and revolver omitted;

Figure 4 is a vertical transverse section taken on the line 4—4 of Figure 2;

Figure 5 is a vertical transverse section taken 20 on the line 5—5 of Figure 2; and

Figure 6 is a perspective view of an adjustable flashlight operating member adapted for use with flashlights having the operating push button at different locations on the barrel or casing thereof.

Referring to the drawing, in which similar parts 25 are designated by like numerals:

The firearm to which the attachment is to be applied is illustrated in Figures 1 and 2 as a revolver of well-known type. It is to be understood, however, that this illustration is merely 30 intended to give an example of the method of applying the attachment; and that the firearm may be of any other type adapted for use with an illuminating aiming device.

The revolver, which is indicated generally by the reference numeral 7, comprises a butt or stock 8 and a barrel 9, with the usual trigger 10 and trigger guard 11 forming part thereof. The flashlight intended to be detachably connected to the 40 revolver 7 is designated by the reference numeral 12. The support for the flashlight 12 comprises a strip 13 of sheet metal, or other suitable material, slidably connected to a strip 14. The strip 13 is provided at its rear end with a slot 15 (see 45 Figure 2) through which extends the shank 16 of a bolt 17, which is screwthreaded into an aperture formed in the plate 14. A wing nut 18 threaded onto the shank 16 of bolt 17 serves to clamp the slotted end of the strip 13 against the 50 strip 14.

The forward end of the strip 14 is provided with a slot 19, through which extends the screw-threaded shank 20 of a machine screw which is threaded into the strip 13. A wing nut 21 is 55 wedged to or otherwise fixed to the lower end of the screw 20, and facilitates the turning of the screw to clamp the outer end of the strip 14 against the strip 13. The invention is not particularly concerned with the details of the clamp- 60

ing nut, since any other equivalents of the same may be used for clamping the two strips 13 and 14 together in lengthwise adjusted positions.

The rear end of the strip 14 is bent upwardly 5 to form a flange 22. This flange is bent to conform generally to the curvature of the end of the butt 8, and is provided with adjustable screws 23 and 24, pointed at their inner end to contact with the end of the butt 8, which may be provided with conical depressions 25 and 26, to receive the pointed ends of the screws 23 and 24, respectively.

To clamp the gun butt 8 firmly against the flange 22, or against the screws 23 and 24 thereof, there is provided a plate 26' mounted to slide on the upper surface of the rear end of the strip 14. A machine screw 27 secured at one end to the plate 26', has a screwthreaded shank extending freely through a slot 28 formed in the strip 20 14. A wing nut 29 serves to clamp the plate 26' in adjusted position on the rear end of the strip 14. Screws 30 and 31 similar to the screws 23 and 24 are adjustable through an upwardly turned flange 32 on the end of the plate 26' into 25 contact with the butt 8 to effectively secure the butt 8 in position at the end of the strip 14. A screwthreaded rod R extends from the end of the plate 26' through an aperture at the lower end of flange 22, and a wing nut N on rod R serves 30 to adjust said plate 26' and its flange 32 into clamping position against butt 8.

The barrel 9 of the gun is secured to the strip 14 (see Figure 4) by a standard designated generally by the reference numeral 33. This standard 35 comprises an angle iron having a flange 34 suitably secured as by a screw 35, to the lower strip 14. The other member 36 of the angle iron is provided with a slot 37, and extends substantially perpendicularly to the strip 14.

Extending upwardly from the member 36 there 40 is a member 38 of substantially the same width as the member 36. The lower end of the member 38 is provided with a tongue 39 which fits snugly and slidably in the slot 37. A bolt 40 extends through the slot 37, and is provided with a wing nut 41, by means of which the members 36 and 38 may be clamped together in lengthwise relatively adjusted positions.

The upper end of the member 38 is bent to 45 form an angular flange 42, in the angle of which the gun barrel 9 is adapted to be seated. The upper end of the member 38 is also provided with a slot 43 adapted to receive slidably the shank of a bolt 44. A clamping member 45 of substantially the same width as the member 38 50 is adapted to slide lengthwise of said member 38 along the slotted portion thereof. The member 45 is provided with a tongue 46, which fits snugly and slidably into the slot 43. The head 55 of the bolt 44 is secured to the clamping member 45, and a wing nut 47 on the bolt 44 serves to clamp the member 45 in adjusted position on the member 38.

It will be apparent from Figure 4 of the drawing 55 that the angular clamping members 42 and 45 are shaped so as to provide for the reception of gun barrels of different sizes. It will also be apparent that the adjustable connection between the members 36 and 38 provides for the adjustment of the gun barrel into substantial parallelism with the strips 13 and 14.

To facilitate the aiming of the firearm 7 at night or in dim light, there is mounted on the strip 13 the flashlight 12. It is obvious that this flashlight must be mounted in such position with

respect to the gun barrel 9, that the distinctive spot in the beam of light and the projectile of the firearm will intersect on the target. Accordingly, the flashlight must be provided with some means for adjustably mounting it on the support 13, 5 which as previously described, occupies a position substantially parallel with the axis of the barrel 9.

At its rear end the flashlight 12 is seated between the arms 48 and 49 of a U-shaped spring 10 clip which is designated generally by the reference numeral 50 (see Figure 4). The clip 50 comprises a pair of upwardly extending members 51 and 52 forming extensions of the arms 48 and 49, respectively, and connected at the lower ends 15 by a transverse member 53. The arms 48 and 49 can be adjusted toward and from each other by means of the screw 54 which connects the spring members 51 and 52 near the upper ends thereof. 20

A screwthreaded rod 55 is secured at its lower end to the strip 13, and this rod passes freely through an aperture formed centrally in the transverse member 53. A pair of nuts 56 and 57 are threaded onto the rod 55 on opposite sides 25 of the member 53 and serve to secure the clip 50 in vertically adjusted position with respect to the strip 13.

The forward end of the flashlight 12 is received between the arms 58 and 59 of a spring clip 30 designated generally by the reference numeral 60. The arms 58 and 59 are connected at their lower ends by a transverse member 61 which is provided with a slot 62 extending substantially throughout the length thereof. An externally 35 screwthreaded sleeve 63 is threaded into the strip 13, and at its lower end is provided with flattened portions 64 and 65 adapted to receive a wrench for the purpose of turning the said sleeve in the strip 13. 40

A bolt 66 extends through the sleeve 63, and the head 67 of the bolt extends across the slot 62 in the member 61. A wing nut 68 on the screwthreaded shank of the bolt 66 serves to clamp the member 61 securely against the upper 45 end of the sleeve 63. It will be apparent from the construction of the flashlight support members that both ends are mounted on the strip 13 for vertical adjustment toward and from the barrel 9 of the firearm. In addition to this vertical adjustment the slot 62 in the member 61 provides 50 for such transverse adjustment of the forward end of the flashlight 12 as may be necessary to bring the beam of light into parallelism with the axis of the barrel 9. 55

The clip 60 is provided with an adjusting screw 69 similar to the screw 54, for adjusting the arms 58 and 59 into clamping position on the forward end of the flashlight 12. That portion of the screw 69 between the arms 58 and 59 constitutes a pivot for one end of a trigger 70 which is located to be swung about said pivot into contact with the button 71 for operating the flashlight 12. The lower end of the trigger 70 is provided with a slot adapted to receive therein a 60 spacer between two ball members of a chain 72 of common construction. 65

The trigger 70 normally hangs by gravity out of contact with the flashlight operating button 71. The chain 72 extends lengthwise of the strips 70 13 and 14, and is connected at its other end to a flange 73 which projects upwardly from a plate 74. The plate 74 is mounted to slide over a flange 75, which may be secured as by screw 76 in any one of a series of screw-threaded apertures 77 75

6. 41

2,140,880

3

formed in the strip 14. The flange 75 is provided at its opposite edges with upturned lugs 78 and 79, and a pin 80 extends through said lugs and across the plate 74 to maintain it in sliding contact with the flange 75. The flange 75 at its rear end is connected to an upwardly turned flange 81 which is slotted to permit the sliding movement of the plate 74 therethrough.

The upturned flange 81 has a screwthreaded rod 82 fixed thereto by means of a lock nut 83, and the rod 82 passes freely through an aperture 84 formed in the upturned flange of the trigger plate 74; and a nut 85 is adjustable on the rod 82 to limit the forward movement of the plate 74 under the influence of a compression spring 86 which surrounds the rod 82 between the fixed flange 81 and the upturned flange on the plate 74.

The plate 74 is bent downwardly toward the rear end of the strip 14 to slide on the upper surface thereof, and is then bent upwardly to form a hook 87 adapted to be engaged by a finger of the operator for the purpose of exerting tension on the chain 72 sufficient to move the trigger 70 against the flashlight button 71. As shown in Figure 2 of the drawing the strip 14 is provided with a series of screwthreaded apertures 35' to provide for the bodily adjustment of the standard 33 lengthwise of the strip 14. Flashlights of different length are provided for by a second and maybe a third threaded hole in plate 13 to receive threaded sleeve 63.

As so far described, the attachment is provided with means for positioning the flashlight in accordance with variations in the type of firearm. In order to provide for the use of flashlights of different length, I have designed a flashlight operating trigger designated generally by the reference numeral 88 (see Figure 6). This trigger is adjustable to flashlights having the push button 40 at different locations on the flashlight barrel.

The trigger 88 comprises a plate 89 slotted throughout the greater part of its length to receive a contact screw 90 adjustable, along with slot 91, into proper position to make contact with the flashlight operating button 71 when the trigger 88 shall have been substituted for the trigger 70. The forward end of the plate 89 is provided with a pair of downwardly projecting lugs 92 and 93 which are apertured to receive the pivot rod or screw 69. The other end of the plate 89 is bent downwardly at substantially right angles to form a flange 94. This flange 94 is provided with a slot 95 in which is slidably received the shank of a screw 96 which extends into the rear part of a U-shaped member 97. The arms 98 and 99 of the member 97 have a pivot rod 99' extending therethrough to form a pivot for a substantially U-shaped trigger member 100. The free end of the trigger member 100 is provided with a slot 101 to receive one of the spacer links in the chain 72. It is believed the operation of this flashlight operating member 88 will be obvious from an inspection of the drawing.

Numerous variations may doubtless be devised by persons skilled in the art without departing from the principles of my invention. I, therefore, desire no limitations to be imposed on my invention, except such as are indicated in the appended claims.

What I claim is:

1. A firearm having a barrel and a stock, a support, adjustable means for detachably clamping one end of said support to the stock, means for detachably connecting said support to the

barrel and substantially parallel to said barrel, a casing having means therein for directing and focusing a beam of light, and means for mounting said casing between said barrel and support on the support, said means being adjustable to vary the angle of the beam of light with respect to the axis of the barrel.

2. A firearm having a barrel and a stock, a support, adjustable means for detachably clamping one end of said support to the stock, means for detachably connecting said support to the barrel and substantially parallel to said barrel, a casing having means therein for focusing and directing a beam of light, a pair of standards adjustable perpendicularly to said support and having means at their upper ends for clamping said casing thereon between said barrel and support, means for adjusting each of said standards toward and from said barrel, and means on one of said standards for adjusting the clamping means connected thereto laterally of said barrel.

3. A firearm having a barrel and a stock, a trigger, a support, adjustable means for detachably clamping one end of said support to the stock, means for detachably connecting said support to the barrel and substantially parallel to said barrel, a casing having means therein for focusing and directing a beam of light, means for mounting said casing on said support and between said barrel and support for adjustment with respect to said barrel in two directions, and means slidably mounted on said support adjacent to said stock and trigger for operating the light directing means in said casing.

4. A firearm having a barrel and a stock, a trigger, a support, adjustable means for detachably clamping one end of said support to the stock, means for detachably connecting said support to the barrel and substantially parallel to said barrel, a flashlight comprising a casing having means therein for generating and focusing a beam of light and a button extending through the casing to control the operation of said means, a pair of standards mounted on said support and having clamps at their upper ends for securing said casing in position on said standards, and means slidably mounted on said support adjacent to said stock and trigger and connected to said button for operating the light generating means in said casing.

5. The device set forth in claim 4, in which said support is extensible lengthwise, in combination with means for fixing said support in any position of extension.

6. The device set forth in claim 4, in which said support comprises a pair of strips, one slidably mounted upon the other, with means for clamping said strips to each other in any desired position of lengthwise extension.

7. A firearm having a barrel and a stock, a support comprising a strip of material having a flange at one end thereof, a member slidable on said strip toward and from said flange to clamp the end of said stock against the flange, said strip extending substantially parallel to the barrel, a pair of standards adjustable perpendicularly to said strip, means at the upper end of said standards for detachably securing a flashlight thereto, a trigger slidable on said strip adjacent to the stock clamping end thereof, and means connecting said trigger to said flashlight for controlling the operation thereof.

CARL BENTON OSBORN.
